(57) **CLAIM**

What is claimed is the ornamental design for a trampoline enclosure, as shown and described.

DESCRIPTION

FIG. 1 is a perspective view of the trampoline enclosure; FIG. 2 is a side view of the trampoline enclosure; and, FIG. 3 is a top view of the trampoline enclosure.

The cross-hatch is used to illustrate a textured surface, without reference to any specific texture or color. The broken lines showing certain features are for illustrative purposes only, and form no part of the claimed design.
